UNITED STATES PATENT OFFICE.

DWIGHT H. BENNETT, DECEASED, LATE OF BROOKLYN, NEW YORK, BY JAMES L. BENNETT, ADMINISTRATOR, OF BROOKLYN, NEW YORK.

GAS-ENGINE.

1,118,178.

Specification of Letters Patent. Patented Nov. 24, 1914.

Application filed March 25, 1914. Serial No. 827,222.

To all whom it may concern:

Be it known that I, JAMES L. BENNETT, a citizen of the United States of America, residing in the borough of Brooklyn, county 5 of Kings, and State of New York, administrator of the estate of DWIGHT H. BENNETT, deceased, who did in his life invent certain new and useful Improvements in Gas-Engines, do declare that the following is a 10 specification.

Said invention relates to gas engines of the class called turbines, and it consists in the devices and combinations of devices hereinafter described and claimed.

Figure—1 is a side elevation of such engine, embodying the invention. Fig.—2 is a vertical longitudinal sectional view of the same. Fig.—3 is a detailed view of the clutch mechanism interposed between the 20 fan carrying shaft of the compression mechanism and the gear wheel which is connected with the actuating power. Fig.—4 is a vertical cross-sectional view of line 4, 4, of Fig. 2. Fig.—5 is a cross-sectional view 25 of one of the vanes employed. Fig.—6 is a vertical longitudinal sectional view of the air inlet and compression devices. Fig.—7 is a detailed view of one of the perforated tubes of the carbureter.

The outer casing or cylinder of the engine is indicated at 1. It has a head, 2. Concentric with the outer casing is constructed an inner cylinder, 3, 4, one part—3—extending from head, 2, for a considerable distance, 35 inward where it abuts against a rim of a set of blades, and the other part, 4, from the rim of the succeeding set of blades to a point in line with the further end of casing, 1, where the space between them is closed, 40 by an annular head, 5. The space between 1 on the outside and 3 and 4 on the inside, is intended to constitute a water jacket for the engine. From the outer face of the annular head 5, another cylinder 6, extends 45 longitudinally outward and is closed by a head 7, having a central bore to accommodate the shaft 8, and its sleeve 9. This cylinder 6 is pierced at a number of places, here sixteen, and the walls of each such 50 aperture are surrounded by flanges, 10, to the outer edges of which is secured an an-

nular cylinder, 11, the interior face of which is apertured to register with the flanged apertures of cylinder 6.

In the heads 2 and 3 which are centrally bored for the purpose, the main shaft, 8, is mounted, one end carrying a sleeve 9 and the other a sleeve 12, entirely independent of sleeve 9. Bosses or other devices to constitute sufficient bearings for the sleeve 60 shaft, are preferably formed on the heads 2 and 7, but if such bearing should be insufficient, the shaft could readily be extended and mounted in pillow blocks or other suitable supports. Sleeve 9 is fitted as 65 closely to the shaft as possible without causing undue friction, and extends from a point some inches without the line of head 7 to a point slightly within the line of head 5 of the main cylinder. At the inner end, 70 it carries a circular disk 13, rigidly secured to it and of a diameter to fit closely within the cylinder 4. Next in succession to disk 13, surrounding said sleeve 9, a wheel is placed composed of a hub 15, radial partition arms 16, an apertured disk 17 covering its outer face and a partial rim in the form of a flange 18 extending inward from the edge of disk 17 over the edges of arms 16, to a line just within that of the circle of 80 apertures in cylinder 6. The inner outer corners of the arms 16 are secured rigidly to a ring 19, triangular in cross section (as shown in Fig. 2) which is in turn secured to the cylinder 4 and head 5 and projects 85 outward toward head 7 and in line with rim 18 to a line just beyond that of the inner side of the circle of apertures in cylinder 6 and inward toward shaft 8, to a line within the line of the circumference of disk 13. 90 This ring 19 may be cast with and as part of arms 16 and bolted in place or as part of cylinder 4 or head 5. Its exact construction is not material in that regard, its main purpose being to attach the partitions 16 the 95 hub, 15, the disk 17 and rim 18, firmly to the stationary cylinder and thus hold them stationary, and, in conjunction with said hub, partitions and disk, to constitute a series of chambers to be more particularly described hereafter.

Beyond disk 17, a partition 14 extends

from the wall of cylinder 6, inward to a close fit with sleeve 9. It has a series of apertures 22 corresponding in number, size and relative location with the apertures 24 formed in disk 17. Between disk 17 and partition 14, a third disk 20, is located rigidly secured to sleeve 9, so that its movement may be synchronous with that of disk 13, and so nearly filling the space between 10 17 and 14 as to just permit its turning without friction between it and them, and extending outward to the inner face of cylinder 6 and there flanged or connected to a flange 21, which extends inwardly, parallel 15 with the shaft, between flange 18 and the outer face of ring 19 on the one side and cylinder 6 on the other, to a line beyond the circle of apertures in cylinder 6, and substantially to head 5. Disk 14 is provided 20 with a number (here 16) of radially cut apertures, 22, evenly spaced, cut from near the center outward, for a distance usually (but not necessarily) about one-sixth of the diameter of said disk, the width being about 25 equal to the space between the arms or partitions 16. Disk 17 is also provided with radially cut apertures 24, of a length and width corresponding to the length and width of apertures 22. Disk 20 has four 30 radial apertures, 25, evenly spaced and in length equaling apertures 22 and 24, with which they register, but in width equal to the space between alternate arms 16, that is to the space occupied by two apertures, 35 minus the width of the walls, and its flange, 21, is provided with four apertures evenly spaced which will at appropriate times register with the apertures in flange 18 and cylinder 11.

40 Disk 13 has four radial apertures, 23, corresponding in width with the space between partitions 16, plus the thickness of the partitions and in length extending from quite near the sleeve 9 to a line just within 45 that of ring 19. For a short distance within disk 13, the cylinder 4 is left vacant to form a reservoir of power, 99. Succeeding space 99, there is a circular series of vanes 26 secured to a sleeve or hub 27 surrounding shaft 8 and provided with a rim 28, which as here shown constitutes the cylinder itself. Closely following vanes 26 is a second series of vanes 29, but these, are secured rigidly to shaft 8 and their pitch is 55 the reverse of that of vanes 26. Their rim 30, is quite heavy and is chambered or rabbed to fit a corresponding chamber or rabbet in the edge of cylinder 4, thereby substantially constituting rim 30, a continuation of said cylinder. On the side opposite to that adjoining cylinder 4, the rim 30 is also chambered and there makes contact with a band 31 supported by brace, 32, which may be in the form of a ring ex-

tending to cylinder 1 and pierced with many 65 apertures. Similar braces, 34 and 41, strengthen and support in place respectively the inner ends of parts 3 and 4 of the inner cylinder.

Sleeve 12 extends inward on shaft 8 to 70 the line of the nearest edge of vanes 29 and mounted on said sleeve adjacent to said vanes 29, there is a third series of vanes 35, having a rim 36 chambered as described to fit on one side against the chambered surface of band 31 and that of cylinder 3 on the other. The pitch of vanes 35 is, in general, similar to that of vanes 26. Succeeding vanes 35, are fixed partitions, 37, extending radially from a hub 38, surrounding 80 sleeves 12, to and secured to the shell 3. The space 39 between the outer line of partitions 37 and head 2, is an open chamber and from it, an exhaust pipe 40 extends to a convenient point of discharge.

85 A flywheel 42 is mounted on shaft 8 and in a bracket 43 is mounted a shaft 44 carrying a gear wheel 45 and a pulley wheel 46. Gear 45 meshes with a gear 47 mounted on sleeve 12 and pulley 46 carries a belt 48 running to 90 a shaft 8 and thereby any power developed by the movement of vanes 35 will be transmitted to shaft 8.

95 Sparking plugs are located in each explosion chamber, but their operation need not be described, as they are fully set forth in a previous application, S. N. 349,773.

54 is the carbureter. It consists of a long tube open at one end and at the other end communicating with the equalizing chamber 100 53 lying within cylinder 6 between head 7 and disk 14. In standards 55 in said tube, a shaft 56 is mounted and on that shaft a balance wheel 57 whose spokes 58 are vanes, and a series of fan blades 59 all pitched in 105 the same direction. Radial partitions 60 of slight width but appreciable length, in a direction parallel with the shaft 55, are interposed in the series of fans to interrupt the 110 too great rotary motion the air would otherwise acquire. Gear 61 on shaft 56 meshes with gear 62 on shaft 63, which in turn carries gear 64 meshing with gear 65 on shaft 66, which, through pulley 67 and belt 68 about 67 and shaft 8, would communicate 115 power to move the fans, but gear 61 is not rigidly connected with shaft 56, but loosely thereon, and intermediate the two gears there is a clutch 69 secured to said gear 61. When gear 61 turns with a sufficient speed, the clutch will seize shaft 56 and revolve it and its burden, but if the speed of gear 61 should decrease, shaft 56 nevertheless, under its acquired momentum and that of its balance wheel 57 may for a moment continue 120 at the higher speed independently of the gear 61, but cannot reverse unless 66 were reversed.

In the carbureter, in advance of the fans, are one or more atomizers. They consist of two heads, 70 joined by a rim and by a series of tubes 71. These tubes are pierced by numerous fine holes 72. Then a small tube 73 leads from the carbureter to the upper part of the tightly closed gasolene tank (not shown) and another tube 74, shorter than tube 73, leads from the lower part of said tank to the space between heads 70.

On that part of shaft 8 projecting out through head 7 and beyond the sleeve 9, a friction disk 75 is mounted. In two brackets, 76 and 77, projecting from head 7, a shaft 78 is mounted feathered on shaft 78, but free to move up and down thereon, I mount a friction wheel 79, so placed and arranged as to make frictional contact with disk 75. Near the upper end of shaft 78 there is a second friction wheel 80 and on a shaft 81, extending from a foot secured to head 7 and braced by an arm 82 extending down from bracket 77, there is a second friction disk 83 placed and arranged to make contact with wheel 80. Shaft 82 also carries a pulley wheel 84 about which a belt 85 extends to and about the extended part of sleeve 9 outside of head 7. The bracket 77 is bifurcated or forked and through its tines is passed a threaded screw 86 provided with a crank 87. The thread of screw 86 carries an arm 88, from the end of which a cord or line 89 extends down to the hub wheel 79, to which it is securely attached by means of a ring or collar thereon.

Shaft 8 is hollow for a considerable portion of its length and a tube 90 is connected to its open end by a suitable joint. From the space 93 within the hollow shaft, tubes or channels 91 extending through the thickest parts of vanes 29, lead to the open space between rim 30 and cylinder 1. Similar tubes or channels 92 lead through the thickest parts of vanes 35 and open into the same at their inner ends. These channels 92 extend through sleeve 12 and register with a series of ports 94 cut from space 93 to the surface of the shaft; but to insure that the passage shall not be cut off by the turning of the shaft 8 in sleeve 12, the face of the shaft is turned down for a distance on each side of ports 94, and other ports 95 lead from space 93 to the face of the turned part of the shaft. A discharge tube 96 extends through head 2 into the space 97, between cylinder 1 and 3, and another discharge tube 98 leads from the annular cylinder 11.

The operation of the engine is as follows: Motion must be communicated to shaft 56 to charge the chamber 53. Gasolene having been forced by any suitable means from the tank to the carbureter proper, the air forced

in by the movement of the vanes 59 will, in 65 passing through tubes 71 become charged with the gas making material issuing from holes 72 and will pass on and into equalizing chamber 53 as an explosive compound. Further motion of shaft 56 and its vanes 59 70 will compress the mixture in chamber 53. Now the shaft 8 is also started and through the connections already mentioned its motion will be communicated to sleeve 9 and its rigidly attached disks 20 and 13, their motion being of course always synchronous. The motion of the disk 20 will speedily cause it to begin to uncover apertures 22 and 24 and thereby provide free passage for the explosive mixture from chamber 53 into four 80 evenly spaced chambers. Not only so, but as disk 20 moves on, it will uncover the four chambers, respectively succeeding those first uncovered and thus throughout its motion. When four chambers have thus been filled 85 under pressure, the further movement of disk 20 will close the entrance ports and at the same instant the movement of disk 13 will begin to open ports 23 of said four chambers, the positions of disk 13 and disk 20 being so adjusted on sleeve 9 as to produce such effect. When apertures 23 are about one-third open (any other distance may be selected if desired) sparks are created at the spark plugs and the charges in 95 those four chambers are fired. The gases produced by the explosions rush through ports 23 into chamber 99 and thence between the entire series of vanes 26, then 29 and then 35 and the pitch of each succeeding 100 set of vanes being reversed, such passage will cause the vanes 29 to rotate in one direction, carrying the shaft 8 with them, and the vanes 35 to rotate in the opposite direction, carrying sleeve 12 with them, such 105 power as is developed by such rotation of sleeve 12 being added to the shaft power through gears 47 and 45, pulley 46 and belt 48.

When the explosion has taken place and 11 the gas passed out as described, disk 13 again closes ports 23 and in due course the movement of disk 20 brings the apertures in its flange 21 to register with the said four discharge chambers, and any remaining gas 11 therein may escape through the flanged ports in cylinder 6 and into and through the annular chamber 11 and out of its exhaust 98, being hastened in that movement by the fresh incoming explosive mixture which will 1 by that time be again entering those chambers under pressure. The respectively succeeding four chambers are likewise charged, closed, opened and their charges exploded and delivered into chamber 99 and thence to 1 their work as described, and the cycle continues so long as material is furnished and movement permitted. The purpose of

chamber 99 is to effect a more evenly continuous movement of the vanes and therefore the shaft than if the discharges were directly against the vanes. The gases fill 5 chamber 99 and in it become a species of buffer. From thence they flow against each set of vanes, and not merely ones opposite the discharging chambers. Again the incoming gases add to the general pressure in 10 chamber 99 which acts as a reservoir from which the power is continually proceeding with a less pulsatory character than would otherwise be the case. Meanwhile the shaft 8 has developed motion under the influence 15 named and thenceforth will actuate all of its connected devices, including shaft 56. Its movement, of course, causes the air forced through pipe 73 to create a pressure 20 on the gasoline tank and when the pressure in chamber 53 and tube 54 is momentarily lessened by the opening of ports 22 and 24, that pressure already in the gasoline tank acting through the shorter pipe 74 will cause 25 the gasoline entering below heads 70 to issue in a jet like spray from holes 72 in tubes 71 and thereby continue to furnish the material needed for the explosive mixture. If shaft 8 should momentarily slow down the action of fans 59 would not necessarily be thereby 30 retarded, for the balance wheel may for that moment proceed at its already acquired speed, clutch 69 being always ready to again seize and turn shaft 56, when the speed of shaft 8 again acquires that of shaft 56. As 35 they issue from between the blades 35, the gases will have acquired a rotary motion of considerable force, and might therefore create an objectionable noise if nothing intervened between said blades and exhaust 40 and therefore the radial plates 37 are introduced at this place to guide those gases in the exit and in overcoming the rotary motion named, obviate the objection the noise might otherwise present.

45 To cool the parts a stream of water is introduced through tube 90. It passes thence to and through space 93 and by centrifugal force will flow out through chamber 91 and ports 94 and 95 and channels 92 into chamber 97 and thence to and out of discharge tube 96, thus furnishing a very convenient means for effecting the desired end; and to enhance the cooling effect, supplementary channels are sometimes made in the thick 50 parts of the vanes leading from and to channels 91 and 92 (as indicated in dotted lines in Fig. 4).

55 As will be manifest, there are times when it is advisable to change the rate of explosion, relative to the revolutions of the shaft and this may herein be readily accomplished by loosening the set screw holding wheel 80 in place on shaft 78 and shifting that wheel downward to increase and upward to de-

crease the speed of the sleeve 9 (which governs the rate of discharges relative to the revolutions of shaft 8). If a momentary and rapid change of such relative speeds is desired, it may readily be accomplished (within the limits set by the location of 70 wheel 80) by rotating screws 86 and thereby lifting or lowering arm 88 and its link 89, which will carry wheel 79 to a larger or smaller track upon the face of disk 75 and thus decrease or increase its speed as related.

75 The claims are not limited to the exact form, proportions or arrangement of parts herein as shown and described. Many of them may be changed in various particulars 80 and some may be omitted without departing from the spirit of my invention.

85 The claims are not limited to the number of vanes employed nor to the number of difference series of vanes nor to any other details, other than as set forth in the claims or necessarily implied by the terms used.

What is claimed herein, is—

90 1. The combination of a cylinder having a water jacket about it, a shaft with a channel therein, a pipe leading to said channel, a series of vanes supported on said shaft, a series of channels extending through said vanes from the channel in the shaft to the water jacket, and a pipe leading from said jacket, all substantially as set forth.

95 2. The combination in an internal explosion engine of a cylinder having a water jacket about it, a shaft with a channel therein, a pipe leading to said channel, a series 100 of vanes arranged about said shaft, a series of channels extending through said vanes from the channel in the shaft to the water jacket and a pipe leading from said jacket, all substantially as set forth.

105 3. The combination in an internal explosion engine of a cylinder having a water jacket about it, a shaft with a channel therein, a pipe leading to said channel, a series 110 of vanes arranged about said shaft, a sleeve 110 interposed between said vanes and said shaft, a water chamber about said shaft and within said sleeve, ports leading from the channel in the shaft to said water chamber, a series of channels extending through said 115 vanes from the channel in the shaft to the water jacket, and a pipe leading from said jacket, all substantially as set forth.

120 4. In a gas engine, an explosion chamber, a main tube leading to said explosion chamber, a series of fan blades arranged to revolve in said tube, a small tube leading from the main tube to the closed gasoline tank, a carbureter in said main tube composed of two diaphragms connected by a series of 125 tubes opening at each end into the main tube and perforated throughout their length, and a second small tube shorter than the first,

leading from the gasolene tank to the space between the diaphragm in the main tube, all substantially as set forth.

5. In a gas engine, a carbureter provided with an internal shaft, carrying a balance wheel and a series of fans, a gear loosely mounted on said shaft, and an automatic clutch interposed between said gear and said shaft, all combined substantially as described.

In testimony whereof, I have signed my name to this specification in the presence of

two subscribing witnesses, this fourth day of February, 1910.
